UNITED STATES PATENT OFFICE.

ALEXANDER L. SCHRAM, OF HILLSBORO, ILLINOIS, ASSIGNOR TO SCHRAM GLASS MANUFACTURING COMPANY, OF ST. LOUIS, MISSOURI, A CORPORATION OF MISSOURI.

FEEDING ATTACHMENT TO PUNCH AND DIE PRESSES.

1,171,359.

Specification of Letters Patent.

Patented Feb. 8, 1916.

Application filed October 6, 1914. Serial No. 865,296.

To all whom it may concern:

Be it known that I, ALEXANDER L. SCHRAM, a citizen of the United States, and resident of Hillsboro, Montgomery county, 5 Illinois, have invented certain new and useful Improvements in Feeding Attachments to Punch and Die Presses, of which the following is a specification containing a full, clear, and exact description, reference being 10 had to the accompanying drawings, forming a part hereof.

My invention relates to improvements in feeding attachments for punch and die presses, and the object of my invention is 15 to combine with a press having means for connecting and disconnecting with power, a material feeding mechanism having a means at the press whereby the feeding may be controlled independently of the press.

20 With the above purposes in view, my invention consists in certain novel details of construction and arrangement of parts hereinafter fully described, pointed out in my claim and illustrated by the accompanying drawings, in which:

Figure 1 is a front elevation of a press and a feeding device showing the independent controls therefor; and Fig. 2 shows in 30 plan the gear drive of the feeding mechanism, the clutch therefor being shown in section.

Referring by numerals to the accompanying drawings: 5 designates the table or bed plate of the press, and 6 the supporting 35 frame therefor. At the bottom and to the right hand side of the frame there is a pedal 7, spring operated in one direction and having a rod 8 connected therewith which is provided for the control of the 40 press, so far as its connection and disconnection with power is concerned. The press and the pedally operated control in their specific constructions form no part of my invention.

45 To one side of the press I arrange a column 9, which supports a tank 10 adapted to contain a lubricant, and in which I mount a plurality of rollers 11 in arcural arrangement for the support of a roll 12 of sheet 50 metal. Contiguous to the tank 10 I provide the shafts 13, one above the other, and mount thereon the feed rollers 14, which are intergeared as at 15.

Arranged lengthwise of the tank 10 is a

shaft 16, having the bevel gear connection 55 17 with one of the shafts 13, and carrying a clutch, comprising a flanged disk 18, secured to the shaft 16, to rotate therewith, and a pulley 19, loosely mounted on said shaft. The outer and inner peripheral faces 60 of these two clutch elements are normally held separated by an extensible coil spring 20, and in order to bring the elements together to rotate conjointly I provide the pulley 19 with a hub 21, having an annulus 22 in 65 which the furcated lever 23 engages. This lever 23 is fulcrumed in a bracket 24 extended downwardly from the extended tank sides bearing the feed rollers 14, and is preferably held to its one limit of movement by 70 a spring, such as 25.

26 designates a power shaft, from which belts, such as 27, extend for driving the press and feeding mechanism.

At the left hand side of the press, pivotally secured to the frame 6, is a pedal 28, and extending therefrom to the free end of the lever 23 at the feeding mechanism is a flexible connection 29, directed by pulleys 30.

In the practical operation of the press and feeding mechanism shown and as just described in detail, it is to be borne in mind that the direct feed to the machine is manual and that my feeding attachment, with its control independent of the press, serves to 85 supply the operator with the desired quantity of material from the roll. Among the advantages arising from this feeding mechanism are that the operator is relieved from the labor incident to manually drawing the 90 material from the roll and that the feeding, that is the drawing of the material from its roll and through the body of lubricant in the tank, may be controlled independently of the press, so that the feeding may 95 be proportionate with the demands of the press.

Having thus described my invention, what I claim as new therein and desire to secure by Letters Patent of the United States 100 therefor, is:

In combination with a press arranged for connection with power and means for connecting and disconnecting the press with power, a roll supporting oil bath comprising 105 power driven rollers for moving material through the bath and to the bed of the press, a clutch spring actuated in one direc-

tion, a lever connected with the clutch, a pedally operated lever connected with the press and a flexible connection between the lever connected with the clutch and the lever connected with the press, substantially as set forth and for the purposes stated.

In testimony whereof, I have signed my

name to this specification, in presence of two subscribing witnesses.

ALEXANDER L. SCHRAM.

Witnesses:

E. L. WALLACE,
EDWARD E. LONGAN.
